ASH TRAY STAND

Alfred J. Siebers, Quincy, Ill.

Application July 23, 1956, Serial No. 42,351

Term of patent 7 years

(Cl. D85—2)

Fig. 1 is a side elevational view of an ash tray stand, showing my new design;

Fig. 2 is an elevational view at right angles to Fig. 1; and

Fig. 3 is a top plan view thereof.

I claim:

The ornamental design for an ash tray stand, as shown.
